UNITED STATES PATENT OFFICE.

GEORGE W. YANNEY, OF ALLIANCE, AND EARL FRANKLIN OYSTER, OF EAST CLEVELAND, OHIO.

SAFETY-BRAKE FOR AUTOMOBILES.

1,144,877.

Specification of Letters Patent. Patented June 29, 1915.

Application filed October 18, 1912. Serial No. 726,412.

To all whom it may concern:

Be it known that we, GEORGE W. YANNEY, a citizen of the United States, and a resident of Alliance, in the county of Stark and State of Ohio, and EARL FRANKLIN OYSTER, a citizen of the United States, and a resident of East Cleveland, in the county of Cuyahoga and State of Ohio, have invented a new and Improved Safety-Brake for Automobiles, of which the following is a full, clear, and exact description.

Our invention, while applicable to other purposes, is more particularly designed for embodiment in automobiles to prevent the car from running backward in case of failure to apply the ordinary brake.

The device is advantageous, also, in that when the car is left standing on a grade it can be started from a standstill instead of requiring to be started against any rearward momentum that the car may gain when the ordinary brake is released.

It is the design of our invention to provide a device of the indicated character which will be absolutely automatic and positively arrest any retrograde movement of the car.

The distinguishing features of the invention, and the important structural elements characterizing the preferred embodiment which is illustrated as an example, will be more particularly explained in the specific description hereinafter to be given.

Reference is to be had to the accompanying drawings forming a part of this specification, in which like characters of reference indicate corresponding parts in all the views, and in which—

Figure 1 is a plan view of an ordinary three-speed transmission with our improved device applied thereto, the gear case being shown in section; Fig. 1^a is an end view, essentially diagrammatic, the gear case being omitted; Fig. 2 is a fragmentary plan view of the device with the parts in the arrested position; Fig. 3 is a cross section approximately on the line 3—3 in Fig. 2; Fig. 4 is a sectional elevation showing a slightly different form of the device as applied to a transmission shaft; and Fig. 5 is a similar

view of another form applied to the rear axle.

Referring particularly to Figs. 1, 2 and 3, there is mounted in the gear case 10 a shaft 11 carrying a pinion 12 in position to mesh with a sliding pinion 13 of the transmission gearing, the pinion 12 being keyed to or otherwise made to rotate with the shaft 11. It is to be understood that said sliding pinion operates upon a shaft 13^a which is suitably connected with a source of power such as a gasoline motor. On said shaft also is a sleeve 14 which has limited rotary and axial movement on the shaft 11 and relatively to the pinion 12. The hub of the pinion 12 adjacent to the sleeve 14, and the said sleeve, are formed with coacting interdental cam surfaces and teeth or projections, so formed and correlated that the sleeve 14 will turn with the pinion 12 when the shaft 11 turns forwardly and without any axial movement of the said sleeve; but upon a backward movement of the shaft 11 and pinion 12 the sleeve 14 will be moved axially sufficient to engage the sleeve 14 with a fixed stop 15 attached and supported by the casting and forming a socket for the said shaft 11. Thus the sleeve 14 is intermediate the pinion 12 and the stop 15, and is in the nature of a double box clutch having interdental spaces and clutch teeth, and the formation of the hub 16 of the pinion 12 similarly constitutes said pinion a rotary clutch member. Thus, on the hub 16 of the pinion 12 cam surfaces 17 are produced and clutch teeth 18, and on the intermediate clutch sleeve 14 cam surfaces 19 and clutch teeth 20 are produced.

Each cam surface 17 forms the bottom wall of a recess for receiving the corresponding tooth 20 on the sleeve. Each recess of which the cam surface forms the bottom is defined by a forward wall 21 and an opposite or rear wall 22, and a tooth 20 on the sleeve is permitted a rotary movement limited by the said walls 21—22 during an axial movement of the sleeve 14. Thus, upon a forward movement of the shaft 11 and pinion 12 the wall 22 will contact with the adjacent tooth 20 of the sleeve 14 and sim-

ply turn the said sleeve with the shaft and the pinion 12. Upon a reverse movement of the shaft 11 the cam surfaces 17 of the hub 16 will engage the ends of the adjacent teeth 5 20 and move the sleeve 14 axially a sufficient distance to cause ratchet teeth 23 on the opposite end of said sleeve to engage mating ratchet teeth 24 on the opposed face of the stop 15. Similarly the teeth 18 on the hub 10 16 will engage the cam surfaces 19 on the sleeve 14 between the teeth 20 thereof, so that the adjacent teeth on the sleeve and hub respectively co-act with corresponding opposed cam surfaces for the shifting of the sleeve axially to move it into locked engagement with the stop 15.

In the example shown the stop 15 is integral with a bracket 26 which is secured in any suitable manner on the gear case 10. 20 When, again, the shaft 11 is turned forwardly, the reverse movement of the sleeve to that just described will obviously take place; since the sleeve 14 will be turned by the engagement of the teeth 18 and 20, 25 which engagement is maintained while the sleeve is in locked engagement with the stop 15, and the forward turning of the sleeve 14 will now cause a reverse axial movement of the sleeve, by reason of the contact of 30 the inclined opposed surfaces 27-28 on the sleeve and stop 15. It will thus be seen that so long as the pinion 12 is turned forwardly by the slidable transmission pinion 13 the transmission gear may rotate in the ordinary manner, but upon the backward movement of the pinion 13, still in mesh with the pinion 12, the sleeve 14 will lock the pinion 12 with the stop 15 and thus lock the transmission pinion 13 against movement. When 40 it is desired to reverse the vehicle by throwing the reverse gear into action, the sliding pinion 13 is moved by a sliding gear rod 29, as usual, and this will slide the transmission pinion 13 out of engagement with the brake pinion 12, the shifting of the pinion 13 being accomplished in the usual manner, as by 45 a shifting fork 30 on the rod 29.

We provide a means to insure that the transmission pinion 13 will slide into engagement with the pinion 12 when it is again desired to run the machine forwardly, the desirability of such a device being occasioned by the fact that the pinion 12 will be stationary when the sliding transmission pinion 13 is to be thrown into mesh therewith, and the teeth of the said pinions might come opposite each other. For the specified purpose the shifting rod 29 is provided with a brush 31 having wire bristles 32, and 50 the hub 16 of the pinion 12 is formed with an annular series of ribs 33, so that when the rod 29 is shifted to throw the pinions 13 and 12 into mesh, the brush on said rod

will cross the spiral ribs 33 and cause a partial turning of the pinion 12 and shaft 65 11, and thus facilitate the engagement of the pinions 12 and 13.

In connection with the sleeve 14 we may provide a retarding means to prevent a too free rotation of the sleeve 14 with the hub 70 16, and cause it to move axially with a backward movement of the shaft 11. Thus, as best shown in Fig. 3, friction blocks 34 are slidably mounted in a portion 10^a of the gear case, and bear, by their concave inner 75 ends, against the perimeter of the sleeve, the blocks being pressed toward said sleeve by spiral springs 35 housed in the gear case.

In the form shown in Fig. 4, our invention is applied to the shaft 36 leading to the 80 differential from the transmission gear 37. In this construction the shaft 36 has secured thereto a member 38 constituting a rotary clutch member, which desirably is housed in a casing 39 which may be sustained by a 85 depending member 40 from the chassis 41. A stop is provided in this form of the invention consisting of a sliding pin 42 which has a cord or equivalent flexible connection 43 with the usual reverse lever (not shown), 90 so that upon throwing the clutch lever the pin 42 will be moved axially to inoperative position against the tension of an expansion spring 44. Between the rotary clutch member 38 and the stop pin 42 an intermediate 95 clutch member is provided, consisting of a sleeve 14^a, which, like the sleeve 14 previously described, has a limited rotary and axial movement relative to the clutch member 38 sufficient to engage said sleeve 14^a 100 with the stop pin and disengage it therefrom. To shift the sleeve 14^a toward the stop the member 38 is formed with cam surfaces 45 and the sleeve 14^a with mating cam surfaces 46, there being longitudinally disposed shoulders 47-48 formed respectively on the said members 38 and 14^a. The pin 42 at the inner end is beveled and provided with a cam surface 49, and the adjacent end of the sleeve 14^a is formed with recesses to 110 receive the stop pin, the recesses being defined by stop shoulders 50 at one side and cam surfaces 51 at the other. Thus, the cam surfaces 51, upon the forward movement of the shaft 36, will, if the sleeve 14^a 115 and stop pin are in engagement, cause a disengagement of the sleeve from the stop pin by reason of the cam surfaces 51 contacting with the beveled cam surface 49 of the stop pin; while, on the other hand, any backward movement of the shaft 36 will, by reason of the opposed cam surfaces 45-46, shift the sleeve 14^a axially and engage the sleeve with the stop pin, thus locking the parts against further backward movement. 120 When the car is to be reversed, and the re-

verse lever is thrown, the stop pin will be withdrawn by the cord 43 out of the path of the sleeve 14^a and will permit the shaft 36 to reverse in the same manner as described 5 with reference to the construction shown in Figs. 1 to 3.

In the form of construction shown in Fig. 5 the rear axle 52 has a rear wheel 53 mounted in the usual manner thereon, and said 10 axle has keyed or otherwise secured thereto a clutch member 38^a to rotate therewith, the form of which is similar to the member 38 in Fig. 4. Similarly the shaft 52 mounts a sleeve 14^b similar to the sleeve 14^a, and 15 a stop pin 42^a is provided to be operated from the reverse lever by a cord 43^a. The said stop pin is beveled to provide a cam surface 49^a, and the sleeve 14^b is formed with walls 50^a—51^a. Thus, it will be 20 obvious that the shaft 52 is free to rotate forwardly, but upon a backward movement thereof it will be arrested by the axial movement of the sleeve 14^b into locking engagement with the stop pin in the same manner 25 as described with reference to the construction shown in Fig. 4.

Having thus described our invention, what we claim as new and desire to secure by Letters Patent is:—

- 30 1. A brake device for arresting retrograde movement comprising a driving member, a rotatable clutch member connected with said driving member and independently supported therefrom, an independent-supported 35 non-rotating stop, and an intermediate clutch member movable axially on the first mentioned element into engagement either with the rotary clutch member or with the said stop, the opposed ends of the rotary and intermediate clutch members having co-acting 40 means to cause the axial movement of the intermediate member into engagement with the stop when the shaft or other rotary element turns backward, and the intermediate member 45 having means at its opposite end co-acting with the stop to shift the said intermediate member out of engagement with the stop upon a forward movement from the arrested position.
- 50 2. A device for arresting backward movement comprising a driving member, a rotatable clutch member supported independently thereof and connected therewith, a member fixed on said rotatable member and 55 rotating therewith, a stop rigid as to the rotatable element, an intermediate clutch member revolvable by and with the member on the rotary element and movable axially relatively to the said member without total 60 disengagement therefrom, there being means on the said intermediate clutch member to engage with the member on the rotary element, when the latter turns backwardly, for

engaging the intermediate member with the stop, and means on the said intermediate 65 member to engage and co-act with the stop to reverse the said axial movement when the rotary element moves forward.

3. A safety brake device, comprising a clutch member, a clutch stop, and an intermediate clutch member having axial movement relative to said first mentioned clutch member to make connection with said stop, a driving member and a movable member connecting the brake device and the driving 70 member during the forward rotation of said driving member and when said member is neutral, and disconnecting said brake device and the driving member during the reverse rotation of said driving member. 80

4. A brake device for arresting backward movement of a rotary element, comprising a clutch member rotating with said element, a stop, an intermediate clutch member having axial movement relatively to the first mentioned rotary clutch member, and a frictional retarding device to retard rotary movement of the intermediate clutch member. 85

5. A brake device comprising a rotatable 90 element, an independently supported driving member connected therewith, a cam member rigid on said rotatable element, a rigid independently supported stop provided with cam faces in alinement with said cam 95 member and supporting said rotatable element, an intermediate member provided with cam surfaces on either end conforming to the cam surfaces of the rotatable member and the cam stop forming clutch 100 element and connected at all times with the rotatable member and alternately with the cam stop member and means for transmitting the reverse movement of the driving shaft thereto to operate the same. 105

6. In a device of the class described, a rotary element, a clutch member located thereon, a laterally movable clutch member coacting therewith, a stop coacting with the laterally movable clutch member to lock the 110 rotary element against retrograde movement and to automatically cause the release of said laterally movable element and impart return movement thereto upon a forward movement of said rotary element. 115

7. In a device of the class described, a rotary element provided with clutch teeth and interdental spaces, a stop provided with releasing cam surfaces, a movable element operating on said rotatable member and provided with clutch teeth and interdental spaces coacting with the rotatable member and provided with cam surfaces coacting with the stop cam surfaces to automatically release the lock of the rotating element. 120

8. In a device of the class described, a ro-

tary element provided with clutch teeth and interdental spaces, a stop provided with releasing cam surfaces, a clutch element having a rotary axial movement relative to the 5 rotary element and provided with clutch teeth and interdental spaces complementary to those of the rotary element and with lock surfaces and releasing cam surfaces adapted to automatically lock or release the rotary 10 element.

9. In a device of the class described, a rotary clutch element, a rotated clutch element axially movable relative thereto, a stop provided with means for locking said element 15 against reverse movement there being co-acting means on said element and said stop for automatically releasing said lock.
